UNITED STATES PATENT OFFICE.

JESSE D. RICHARDS, OF WABASH, INDIANA, ASSIGNOR OF ONE-HALF TO EDWARD GILLENWATER AND EBER BAKER, OF SIMS, INDIANA.

VEHICLE-BRAKE.

SPECIFICATION forming part of Letters Patent No. 700,089, dated May 13, 1902.

Application filed December 2, 1901. Serial No. 84,334. (No model.)

To all whom it may concern:

Be it known that I, JESSE D. RICHARDS, a citizen of the United States, residing at Wabash, in the county of Wabash and State of Indiana, have invented certain new and useful Improvements in Vehicle-Brakes; and I do hereby declare the following to be a full, clear, and exact description of the invention, such as will enable others skilled in the art to which it appertains to make and use the same.

My invention relates to carriages and wagons, but more particularly to brakes therefor, and has for its object to provide an automatic vehicle-brake.

15 A further object of my invention is to provide a vehicle-brake which operates as soon as there is a backward draft on the shafts or pole of the vehicle.

20 A further object of my invention is to provide a vehicle-brake which is operated as above described when the vehicle is moving ahead, but which does not act when the vehicle is being backed.

25 There are a number of automatic brakes which are controlled by the draft of horses upon the vehicle and which operate when said draft is in a backward direction. The majority of these brakes are efficient so long as the vehicle is moving ahead. As soon, however, as it becomes necessary to back the vehicle the draft of the horse or horses is in a backward direction and the brakes are on, and if the vehicle is to be backed the wheels must slide. It is principally for the purpose of obviating 30 this defect that I have made my present invention, which has for its principal object to provide an automatic vehicle-brake which is controlled by the draft of the horse and which at the same time allows the vehicle to be 35 freely backed.

40 With these objects in view my invention consists in the novel construction of my brake-rod.

45 My invention also consists in certain other novel features of construction and in combination of parts which will be hereinafter fully described and afterward specifically pointed out in the appended claim.

50 Referring to the accompanying drawings, Figure 1 is a perspective view of my invention

in an operative position. Fig. 2 is a detail view of one of my brake rods and shoes.

Like numerals of reference indicate the same parts throughout both figures.

1 indicates the forward axle, and 2 the 55 wheels.

3 indicates the shafts, and 4 the cross-piece, upon which the whiffletree is carried in the usual manner. Secured to the under side of said cross-piece on either side of the whiffle-tree-bolt are the brake-rod 6. Said brake-rod are provided with forwardly-extending loops 7 at about their central points, and the ends of said brake-rod are bent rearwardly at right angles to said rods, and said ends are 65 provided with brake-shoes 8 of any suitable material. It will be noticed that I form the lower portion of my brake-shoes round, as will be fully described.

On the under side of the shafts, opposite 70 the cross-piece, I provide brake-rod guides 9, within which said brake-rod operate. Just outside of said guides and connected to said brake-rod are operating-rod 10, which are held to the shafts by means of staples 11. 75 The ends of said operating-rod are bent backwardly, so that the holdback-straps of the harness may be attached thereto.

80 Connecting with the loops 7 in the brake-rod are spiral springs 12, having their forward ends fastened to the under sides of the shafts. The tendency of said springs is to hold the brake-shoes away from the wheels. I provide stops 13 on the under side of the shafts for the purpose of limiting the backward movement of the brake-rod.

85 Having thus described the several parts of my invention, its operation is as follows: When the horse holds back, the operating-rod press the brake-shoes in contact with the 90 wheels, since the holdback-strap is connected to said operating-rod, and thus the brakes are applied. When, however, it is desired to back the vehicle, the brake-shoes are brought into contact with the wheels, as above described; but the vehicle-wheels turn in the opposite direction and raise the brake-shoes, so that the rounded bottoms thereof merely 95 contact with the wheels, the stops 13 on the under side of the shafts preventing the brake- 100

shoes from bearing against the wheels, as said stops will not permit of any further backward movement of the brake-rod. Thus the vehicle may be backed just as easily as though the same were not provided with any brake whatever.

Having thus described the operation of my invention, I do not wish to be understood as limiting myself to the exact construction herein set forth, as various slight changes might be made therein which would fall within the limit and scope of my invention, and I consider myself clearly entitled to all such changes and modifications.

15 What I claim as my invention, and desire to secure by Letters Patent of the United States, is—

In a vehicle-brake the combination with the brake-shoes of brake-rod connected thereto, loops in said brake-rod, springs secured thereto, the whole arranged whereby, the loops engage the shafts and prevent the brake-rod from turning when the vehicle is moving forward, and which form cranks to draw the said brake-rod into their normal 20 position after the brake-shoes are raised by the backing of the vehicle substantially as described.

In testimony whereof I affix my signature in presence of two witnesses.

JESSE D. RICHARDS.
